Term of patent 14 years

(Cl. D66—1)

Fig. 1.

Fig. 2.

Fig. 3.

Figure 1 is a perspective view of a railway vehicle shown in reduced scale embodying our new design;

Figure 2 is a plan view of the full line portion thereof; and

Figure 3 is another perspective view of the full line portion.

The dominant features of our design reside in the full line portions of the drawings.

The side opposite Figure 1 is identical with the side shown.

We claim:
The ornamental design for a railway vehicle, substantially as shown, and described.
